United States Patent Office

Des. 220,837
Patented June 1, 1971

220,837

VEHICLE

Irving Carl Mattson, Bay City, Mich., assignor to
Aerospace America, Inc., Bay City, Mich.

Filed Jan. 23, 1970, Ser. No. 21,057

Term of patent 14 years

Int. Cl. D12—08

U.S. Cl. D14—3

FIG. 1

FIG. 2

FIG. 3

FIG. 4

FIG. 5

FIG. 1 is an isometric view of a vehicle incorporating the design;

FIG. 2 is a side elevational view of the left side of the vehicle;

FIG. 3 is a top plan view of the vehicle;

FIG. 4 is a rear elevational view of the vehicle; and

FIG. 5 is a front elevational view of the vehicle.

The appearance of the right side of the vehicle corresponds to the appearance of the left side thereof.

I claim:

The ornamental design for a vehicle, as shown and described.
